UNITED STATES PATENT OFFICE

121,804

DESIGN FOR A GENERAL UTILITY STAND

Frank C. Castelli, Carroll Park, and Herman Kesler, Philadelphia, Pa.

Application May 29, 1940, Serial No. 92,674

Term of patent 7 years

To all whom it may concern:

Be it known that we, Frank C. Castelli and Herman Kesler, citizens of the United States, and residents, respectively, of Carroll Park, in the county of Montgomery and State of Pennsylvania, and Philadelphia, in the county of Philadelphia and State of Pennsylvania, have invented a new, original, and ornamental Design for a General Utility Stand, of which the following is a specification, reference being had to the accompanying drawing, forming a part hereof.

In the drawing:

Fig. 1 is a perspective view of a general utility stand, showing our new design; and

Fig. 2 is an enlarged fragmentary perspective view, partially in section, of a joint element thereof taken at line 2—2 of Fig. 1.

We claim:

The ornamental design for a general utility stand, as shown.

FRANK C. CASTELLI.
HERMAN KESLER.
